The ornamental design for a combined knife holder and cutting board, as shown and described.

DESCRIPTION

FIG. 1 is a perspective view of a combined knife holder and cutting board showing our new design;
FIG. 2 is a front elevation view thereof;
FIG. 3 is a rear elevation view thereof;
FIG. 4 is a side elevation view thereof;
FIG. 5 is a top plan view thereof;
FIG. 6 is a bottom plan view thereof; and,
FIG. 7 is an exploded perspective view thereof, the knife shown in broken lines for illustrative purposes only and forming no part of the claimed design.
